METHOD OF MAKING VALVES

Oscar Hedlund, Battle Creek, Mich., assignor to
Wilcox-Rich Corporation, Detroit, Mich., a cor-
poration of Michigan

Application December 30, 1933, Serial No. 704,627

6 Claims. (Cl. 29—156.7)

This invention relates to poppet valves and more particularly to engine poppet valves having an integral head formation of valve material such as to provide an enlarged chamber or area in the valve head.

One object of the invention resides in the making of a poppet valve of the character mentioned in such a way as to facilitate the manufacture of the valve and to provide an economical method of procedure and an improved product.

Another object of the invention resides in the method of making a poppet valve having an enlarged area within the valve head in which a substantially cup-shaped part of valve material is applied while at forging temperature to a cold preformed insert of copper or the like having a head portion substantially representing the inside of the finished valve head, the valve material being then formed down on the insert material after which the stem forming portions of the valve material are stemmed out.

Other objects and advantages of the invention will be apparent from the following description, the appended claims and the accompanying drawing, in which,—

Fig. 1 is a sectional view of the valve material part;

Fig. 2 is a sectional view of the preformed insert;

Fig. 3 is a central vertical section through the dies of a forging press showing the insert as applied to the valve material part before the forging operation;

Fig. 4 is a sectional view showing how the valve material is formed around the insert metal in the forging or swaging operation;

Figs. 5 and 6 are sectional views of a valve in successive stages of manufacture; and

Fig. 7 is a sectional view of a finished valve made in accordance with this invention.

Referring more particularly to the drawing by reference numerals, 10 designates a substantially cup-shaped part or shell of valve material, such as a suitable steel. In accordance with this invention the shell part 10 is first formed by a suitable extrusion or forging process, this part being integrally formed to provide the wall 11 and the top portion 12 which closes one end of the interior chamber or space 13. The wall 11, as shown, is substantially cylindrical on its outer surface although its inner surface is preferably tapered outwardly away from the head end of the part, as shown. The minimum inside diameter of the chamber or

space 13 is about the same as the desired maximum inside diameter of the space to be formed in the finished valve head.

Fig. 2 shows a preformed insert of suitable material having a melting point somewhat below the melting point of the valve material and preferably below the forging temperature of the valve material. Copper or a suitable alloy is preferably used in making the insert 15, which is so constructed as to have an enlarged head portion 16 the diameter of which substantially corresponds to the minimum diameter of the chamber in the part 10. The shape and size of the head portion 16 of the insert is such as to substantially represent the inside dimensions of the chamber to be provided in the finished valve head.

In making the valve, the valve material part 10 is heated to a desired forging temperature, and the insert, while cold, is applied to the part 10 so that the head of the insert is received at the closed end of the part 10.

The valve material is then formed around the insert metal by a suitable forging or swaging operation to provide a structure such as is shown in Fig. 4, in which the approximate formation of the head portion of the insert is retained to give an enlarged chamber in the head of the structure, this chamber being filled with copper. As shown in Fig. 4 the stem forming portion 18 of the valve material is less in diameter than the wall of the part 10 although the portion 18 is a comparatively thick walled short portion which is subsequently stemmed down to form the elongated valve stem.

In forging the parts 10 and 15 together, use may be made of dies of a forging press substantially as shown in Fig. 3, in which 20 designates a punch or upper forging die that can be so operated as to force the parts 10 and 15 downwardly in the lower die 21. 22 designates a guide bushing adapted to receive and center the heated part 10. 23 is an insert supporting rod the upper end of which has a projection that is received in a recess or cavity 24 provided in the preformed insert, the construction being such that the insert is held upon the rod 23 centered with respect to the guide bushing 22. The insert, while cold, is applied to the rod 23 after which the part 10 which has previously been heated to a forging temperature is dropped into the guide bushing, and the punch or upper die then made to descend. Thus the parts 10 and 15 are forced downwardly so as to form the walls 11 of the valve material in and

around the insert, the shape of the forming portion 25 of the lower die being such as to produce the desired formation. The rod 23 is supported by a suitable spring 26, and after the 5 forging operation has been completed, the vertically movable knockout rod 27 may be forced upwardly to remove the forged part from the die.

As previously mentioned the shape and size 10 of the head of the insert is such as to substantially represent the inside dimensions of the space to be made in the valve head. The valve material is formed around the solid insert without substantially disturbing the head portions 15 of the insert since the insert is cold when the head part of the valve material is applied to it. Heretofore it has been proposed to heat an enclosing shell of valve material while containing an insert of copper, and in such cases the 20 copper will either be heated to its melting point and thus rendered ineffective in controlling the inside shape of the valve head, or great care is required in the selection of materials and in governing the temperatures in order to prevent 25 the copper from being heated to its melting point while heating the containing valve material to a proper forging temperature. If the copper is heated to its melting point it cannot retain its shape satisfactorily and it will be de- 30 formed and result in an uneven or irregular formation of the space within the valve. In accordance with the present invention, however, the hot valve material is readily formed around a comparatively rigid core or insert which gives 35 a controlled formation of the inside chamber to be provided in the finished valve, resulting in an accurate and reliable method of procedure and economically producing valves in which the chamber in the head is of the intended size and 40 shape.

After forming the valve material around the insert to produce a structure as shown in Fig. 4, the stem forming portion of the valve material may be stemmed out and the stem end of the 45 valve closed, it being understood that the portions of the copper insert of smaller diameter may be made as long as desired to produce a copper filled valve in which the copper entirely fills the chamber provided between the walls and in the head of the finished valve. However, 50 the present invention is particularly adaptable in the making of a hollow valve containing liquefiable cooling medium such as metallic sodium or cooling salts of the character set forth in the patent to Heron No. 1,670,965. In 55 accordance with the present method, in making a hollow valve having an integral head structure obviating any possibility of leakage of the valve cooling material in the head of the valve, after forming the structure shown in Fig. 4, the structure is heated to the liquefying 60 temperature of the insert which is then poured out of the formed valve material. After this the stem forming portions of valve material are 65 stemmed out without disturbing the cavity in the head by a suitable swaging operation or the like to provide the formation shown in Fig. 5. The stem is then drilled and the outside surfaces machined so as to leave an enlarged portion 70 at the stem end of the valve, as shown in Fig. 6. This enlarged portion is then stemmed down or swaged to close the stem end which may be welded or plugged, after the cooling material 75 is added, thus providing the hollow integral valve 29 illustrated in Fig. 7.

While the method herein described constitutes a preferred embodiment of the invention, it is to be understood that the invention is not limited to this precise method, and that changes may be made without departing from the scope 5 of the invention which is defined in the appended claims.

What is claimed is:

1. The method in the making of a poppet valve comprising forming of valve material an 10 integral hollow part closed at one end, heating said part, forming an insert of a material of lower melting point than the valve material and having a head at one end thereof of larger diameter than the remainder of the insert, applying 15 the insert within the heated part so the head of the insert is applied to the closed end of said part, and forming the valve material around the insert while the insert is in solid form.

2. The method in the making of a poppet 20 valve comprising forming of valve material an integral hollow part closed at one end, the chamber within the hollow part having a minimum diameter substantially as large as the maximum internal diameter of the head of the 25 finished valve, heating said part to forging temperature, forming an insert of lower melting point than the valve material to provide a head at one end of the insert of larger diameter than the remainder of the insert, applying the insert 30 while cold into the said part so the head of the insert is applied to the closed end of said part, forming the said part around the insert, reducing the stem portion of the valve, and machining 35 the valve.

3. The method in the making of a poppet 40 valve comprising forming of valve material an integral hollow part closed at one end, the chamber within the hollow part having a minimum diameter substantially as large as the maximum 45 internal diameter of the head of the finished valve, heating said part to forging temperature, forming an insert of lower melting point than the valve material to provide a head at one end of the insert of larger diameter than the remainder of the insert, applying the insert while 50 cold into the said part so the head of the insert is applied to the closed end of said part, forming the said part around the insert, heating the part with its insert to above the melting point of the insert material and removing the insert 55 material, reducing the stem portion of the valve, and machining the valve.

4. The method in the making of a poppet 60 valve comprising forming of valve material an integral hollow part closed at one end, heating said part to forging temperature, forming a copper insert having a head at one end of larger diameter than the remainder of the insert and of such size and shape as to substantially represent 65 the inside dimensions of the finished valve head, applying the insert while cold to the heated part so the head of the insert is applied to the closed end of the part, and forming the said part around the insert while the insert is in solid form.

5. The method in the making of a poppet 70 valve comprising forming of valve material an integral hollow part closed at one end, heating said part to forging temperature, forming a copper insert having a head at one end of larger diameter than the remainder of the insert and of such size and shape as to substantially represent 75 the inside dimensions of the finished valve head, applying the insert while cold to the heat- 80

- ed part so the head of the insert is applied to the closed end of the part, forming the said part around the insert while the insert is in solid form, melting and removing the insert material, 5 applying a cooling medium to the interior of the valve, and sealing the stem end of the valve to retain the cooling medium.
6. The method of making a hollow poppet valve comprising forming of valve material an integral hollow part closed at one end, heating said part to forging temperature, forming a copper insert having a head at one end of larger diameter than the remainder of the insert and of such size and shape as to substantially represent the inside dimensions of the finished head, supporting the smaller end of the insert, applying the heated part to the insert while the insert is cold, forging the walls of said part around the insert, melting and removing the copper insert, reducing the stem portions of the said part, applying cooling medium within the said part, and sealing the stem end of the valve 10 to retain the cooling medium.

OSCAR HEDLUND.

CERTIFICATE OF CORRECTION.

Patent No. 2,004,528.

June 11, 1935.

OSCAR HEDLUND.

It is hereby certified that error appears in the printed specification of the above numbered patent requiring correction as follows: Page 2, second column, line 71, claim 5, for "a" second occurrence read at; and that the said Letters Patent should be read with this correction therein that the same may conform to the record of the case in the Patent Office.

Signed and sealed this 16th day of July, A. D. 1935.
